US0D1012781S

(12) **United States Design Patent** (10) **Patent No.:** **US D1,012,781 S**
(45) **Date of Patent:** **** Jan. 30, 2024**

(54) **MOTORCYCLE**

(71) Applicant: **Indian Motorcycle International, LLC**, Medina, MN (US)

(72) Inventors: **Michael M. Song**, Maple Grove, MN (US); **Gregory C. Brew**, Minnetonka, MN (US)

(73) Assignee: **Indian Motorcycle International, LLC**, Medina, MN (US)

(**) Term: **15 Years**

(21) Appl. No.: **29/889,789**

(22) Filed: **Apr. 17, 2023**

Primary Examiner — Darlington Ly

(74) *Attorney, Agent, or Firm* — Faegre Drinker Biddle & Reath LLP

CLAIM

The ornamental design for a motorcycle, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front and left side perspective view of a motorcycle embodying our new design;

FIG. 2 is a front and right side perspective view thereof;

FIG. 3 is a rear and left side perspective view thereof;

FIG. 4 is a right side view thereof;

FIG. 5 is a left side view thereof;

FIG. 6 is a front view thereof; and,

FIG. 7 is a rear view thereof.

1 Claim, 7 Drawing Sheets
(7 of 7 Drawing Sheet(s) Filed in Color)
